REFRIGERATED CABINET

Raymond C. Sandin, Winnetka, Ill., assignor to General Electric Company, a corporation of New York

Filed June 14, 1965, Ser. No. 85,735

Term of patent 14 years

(Cl. D67—3)

The back of the cabinet is plain, and the side not shown is the same as the side shown. The dominant features of my design reside in the portions shown in full lines.

I claim:

The ornamental design for a refrigerated cabinet, substantially as shown and described.
